CLAIM

I claim the ornamental design for an automotive hydraulic rod, as shown and described.

DESCRIPTION

FIG. 1 is a Perspective view of an automotive hydraulic rod showing my new design;

FIG. 2 is a Front view thereof;

FIG. 3 is a Back view thereof;

FIG. 4 is a Left-side view thereof;

FIG. 5 is a Right-side view thereof;

FIG. 6 is a top view thereof; and,

FIG. 7 is a bottom view thereof.

The broken lines are only for environmental purposes and form no part of the claimed design.

1 Claim, 6 Drawing Sheets
